UNITED STATES PATENT OFFICE

2,043,775

WINDOW WIPER

Jacob J. Rosen, Brooklyn, N. Y.

Application June 21, 1935, Serial No. 27,723

2 Claims. (Cl. 15—245)

An object of my invention is to provide a simple and efficient window wiper, commonly known as a squeegee, which requires only one strip of gum rubber.

Another object is to provide a device that is quickly and easily inverted when one corner of the rubber blade becomes worn or damaged.

Another object is to provide a device wherein the four corners of one strip of rubber may be used, one pair of corners being protected from possible damage by contact with sharp edges.

The above and further objects will become obvious to those skilled in the art in the disclosure herein given.

In the drawing, wherein like reference characters indicate like parts;

Fig. 1 is a perspective view of my improved squeegee;

Fig. 2 is a transverse section taken on the line 2—2 of Fig. 1; and

Fig. 3 is a section similar to Fig. 2, in which the squeegee is shown inverted.

Referring to the drawing, the squeegee consists of a head 10 which is made up of two metal strips 12 and 14 of any suitable length between which is clamped a rubber blade 16, the blade being longer and protruding slightly beyond both ends of the metal frames 12 and 14. The metal strips and the rubber blade are held together firmly by bolts 18 and beveled nuts 20. The nuts 20 are so beveled as to make a snug fit and prevent any possible contact and scratching to the surface cleaned when the squeegee is passed over it. A tapered handle 22, bent at approximately 45° to the horizontal, is mounted over one of the metal strips and held firmly in place by two bolts 24 such as shown in Fig. 1.

The metal clamping strips 12 and 14 are of different widths, and the clamping surface 22a of the handle 22 is slightly wider than either of the clamping strips. When assembled, as shown more clearly in Fig. 2, the rear edges of the clamping strips 12 and 14 are parallel, protruding slightly beyond one side of the rubber blade, thereby protecting those corners of the blade from possible damage, as when the squeegee is resting and suspended across the rim of a pail. The front edge of clamping strip 14 extends slightly beyond the front edge of strip 12, and the front edge of the handle clamping plate 22a extends slightly beyond that of strip 14. Thus, when assembled, bolts 24 pass through spaced holes slightly in from the front edges of the metal clamping strips and handle clamping plate 55 and through adjacent holes equidistant from the

side edges of the rubber blade. This arrangement affords the most suitable resiliency in which only a slight pressure is required in wiping a glass surface.

If more pressure is applied, the front edge of 5 22a will serve as a stop and a firm backing, as illustrated in dotted lines in Fig. 2.

When the corner 28 of blade 16, which will be the working corner as shown in the arrangement of Fig. 2, has become worn or scratched, 10 a new corner may be put into effect by simply removing the two bolts 24, disengaging the head 10 from the handle clamping plate 22a, and inverting head 10 so that the corner 28 will be on the lower side and become the working corner, as 15 illustrated in Fig. 3. When the corner 28 becomes worn, the entire rubber blade 16 is disengaged from metal strips 12 and 14 by removing bolts 18 and 24, and the blade 16 turned around so that when assembled again, the corners 30 and 32 will 20 be at the front and afford two new corners ready for use.

It is thus apparent that the life of a blade is prolonged, making it efficient and economical to 25 operate.

It is obvious that minor changes of construction may be made without departing from the scope of the claims.

Having thus described my invention, what I 30 claim as new is:

1. A window wiper comprising an elongated rectangular strip of flexible rubber of rectangular cross-section so as to have two wiping corners along each side edge, the strip having a plurality of holes disposed midway between the edges, two 35 elongated clamping plates having holes to register with the holes in the strip, the clamping plates being narrower than the strip and having the holes therein nearer one edge than the other so that one longitudinal edge of the strip may project beyond the plates for engagement with the window pane and the other longitudinal edge may be within and protected by the plates, a handle having an attaching plate overlying one of the 40 clamping plates, and bolts passing through the strip and plates for clamping them together, the parts being capable of assembly with the strip in four positions relative to the handle so that any one of the four wiping corners may be effectively 45 applied to a window pane.

2. A window wiper as claimed in claim 1, wherein the strip has ends projecting beyond the ends of the plates.

JACOB J. ROSEN.
